(57) **CLAIM**

The ornamental design for a dual pet leash splitter as shown and described.

DESCRIPTION

FIG. 1 is a perspective view of a dual pet leash splitter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the dual pet leash splitter where the splitter is in a configuration of use on a dual pet leash.

The broken lines showing the dual pet leash in FIG. 8 are illustrative of environmental structure only and form no part of the claimed design.
